METHOD AND APPARATUS FOR THE PRODUCTION OF A MIXTURE OF A FUEL AND A LIQUID ADDITION, FOR EXAMPLE OIL

Guenther W. Clemens, Hamburg-Nienstedten, Germany, assignor to Esso Research and Engineering Company, a corporation of Delaware

Application April 22, 1952, Serial No. 283,791

Claims priority, application Germany April 27, 1951

2 Claims. (Cl. 137—3)

The present invention refers to an apparatus for the production of a mixture of fuel (gasoline) and a liquid addition, e. g. oil.

In particular types of internal combustion engines for automotive vehicles and likewise for motorcycles, especially in two-stroke engines, a definite quantity of oil is admixed with the fuel, said oil serving to lubricate the cylinder walls of the internal combustion engine. However, it is also possible to add benzol to the gasoline. In the following description of the present invention only the addition of oil will be discussed in detail, as this addition is more difficult on account of the viscosity of the oil.

For dispensing blends of fuel and oil to be used in two-stroke engines several types of installations have become known besides the so-called "mixing can" and special pumps dispensing pre-blended mixtures. These appliances serve to sell blends of no matter what composition, the oil as such being added to the fuel in order to prepare directly two-stroke blends. An essential disadvantage of these methods and appliances consists in the difficulty and/or impossibility of conveying, dosing, and measuring the oil which is likely to become very viscous, particularly at low temperatures.

One of the main purposes of the invention consists in creating a method and apparatus permitting separate storage of fuel and oil, proper dosage and lasting mixture of the two components at any time in any desired quantity, even at low temperatures. The preparation of the mixture may be effected, for example in connection with an electrically operated pump of customary design which need only be fitted with a corresponding supplementary apparatus and will then be able to dispense optionally unblended fuel or fuel blend.

The present invention consists in that fuel is led, for the purpose of preparing a certain quantity of pre-blended mixture of fuel and oil, into the suction side of a conveying apparatus, for example of a geared pump, and that the fuel flows through the conveying apparatus simultaneously with the oil sucked in from the storage container, so that accordingly an intimate mixture of the two components is achieved. This pre-blended mixture which is a thin and easily conveyable liquid is then added in the desired quantity to the fuel preferably directly at the discharge nozzle wherever the full-hose system is being used.

According to one form of execution of the invention a definite quantity of fuel proportional to the predetermined quantity of oil is taken from the fuel being fed to the nozzle. This portion of the fuel is led into the suction side of a conveying apparatus through which it flows together with the sucked-in oil and in which it is blended with the oil to form the pre-blended mixture. This pre-blended mixture is thereupon added to the fuel flow.

This method eliminates the disadvantage common with the methods and appliances previously known, i. e. that the oil has a very low viscosity, particularly at low temperatures, and cannot be conveyed at all, or only with

2

great difficulties. In the pre-blended mixture fuel and oil are already mixed. Accordingly, the pre-blended mixture is a thin and easily conveyable liquid; consequently the dosage of the unblended fuel and of the fuel blend is possible even during the cold season without any difficulties.

In the attached drawing an apparatus for the practical execution of the method according to the present invention is represented as an example, said apparatus being capable of being used in connection with a fuel dispensing pump.

One part of the drawing marked off and designated A represents a dosing device having the task of properly dosing by means of a dispenser 1 (volumeter and/or flow motor) and a mixture proportioner 2 a definite quantity of a pre-blended mixture of fuel and oil proportional to the fuel flow in the desired mixing ratio by means of a control or dosing device 3.

Another part of the drawing marked off and designated B represents the discharge nozzle, viz., the discharge valve 5 and hoses 4 and 6 for unblended fuel and for the pre-blended mixture, respectively. Fuel and oil, when dispensed according to the full-hose principle, are led together directly at the discharge nozzle, so that, if unblended fuel, or a blend of a definite composition is asked for one avoids the remainder of the preceding discharge having a different composition still being contained in the hose, with the effect that the requested unblended fuel or fuel blend would be contaminated with said remainders. It is obvious that the two hoses may also be arranged one inside the other or one next to the other in a combined twin hose.

The third group marked off and designated C represents that part of the device in which the pre-blended mixture is prepared. It consists of an oil container 7, a foot valve 8, pump 10 with suction piping 9, pressure pipe 12 and motor 11, a by-pass 13 with relief-valve 14, dispenser 15 (volumeter with indicating dial mechanism 16), connection pipe 17, fuel pipe 18, fuel proportioner 19 with transfer mechanism 20 actuated by dispenser 15, and fuel pipe 21 to suction pipe 9.

Fuel proportioner 19 may be controlled, after elimination of the dispenser 15, directly from dispenser 1. It is even possible, after elimination of one or both dispensers, 1 and 15, respectively, to actuate the appertaining proportioners 2 and 19, respectively, directly from the volumeter of the pumps. Pump 10 with motor 11 may suitably be arranged inside of or on top of the oil container 7.

In the apparatus illustrated, and described above, the dispensers 1 and 15 and the mixture proportioners 2 and 19 each may be an oval gear, positive placement device of the type as manufactured by Bopp and Reuther of Mannheim-Waldorf, Germany, or a nutating disc device as manufactured by the Buffalo Meter Co., 2917 Main St., Buffalo, N. Y., sold under the trade name "Niagara" and illustrated and described in Bulletin 30 published by the Buffalo Meter Co., in July 1950. As described in the bulletin referred to, such equipment may be employed not only for registering flow in a main flow line but also as a means to control proportional flow in a related flow line. If one such device drives another of the same or similar nature, the first functions as a motor, and the other as a pump. This relationship is indicated in the drawing between the driving elements 1 and 15, and the pump elements 2 and 19. In the drawing also, the dosing device 3 is a geared variable speed motion transmission means, wherein a shaft connection from the fluid motor 1 drives a shaft connection to the pump element 2 through any selected combination of gears provided by the transmission means. A transmission means of the character contemplated is designated by the num-

eral 26 in the drawing of German Patent No. 663,406, dated August 5, 1938.

The connection between the motor or driving mechanism 15 and the pump mechanism 19, as stated, is similar to that between the similar devices 1 and 2 respectively. In this arrangement, however, the driving and driven shafts are directly connected through the transfer mechanism 20. As shown, a bevel gear on the shaft between 15 and 19 meshes with a bevel gear mounted on the drive shaft of an indicating or recording instrument such as designated by the numeral 16.

The device functions as follows: Motor 11 of the pump 10 is suitably connected in such a manner, that it starts operating only prior to the dispensing of blended or unblended fuel. If unblended fuel is dispensed, it flows through the metering device of a dispensing pump not shown and through volumeter 1 or through a secondary pipe line (not shown in the drawing) by-passing volumeter 1 and subsequently through dispensing hose 4 to dispensing nozzle 5. The proportioner 2 being adjusted to zero by means of dosage apparatus 3 blocks the passage of pre-blended mixture. Simultaneously pump 10 does not operate at all or circulates the liquid through by-pass pipe 13. In the other parts of the system, both fuel and oil are at rest.

If, however, the dosage apparatus 3 is adjusted for dispensing a two-stroke mixture containing m parts of oil, and if the pre-blended mixture to be prepared is to consist, for example of as many parts of oil as of fuel, proportioner 2 sucks in, by way of connection pipe 17 and dispenser 15, a quantity equivalent to $2m$ parts of pre-blended mixture from pressure pipe 12 of pump 10. At the same time dispenser 15 by means of the transfer gear mechanism 20 actuates fuel proportioner 19 which is so adjusted that it draws m parts of fuel from the fuel flow leaving volumeter 1 and which are led by way of 18 and 21 into the suction pipe 9 of pump 10. As a quantity of pre-blended mixture equivalent to $2m$ parts is being drawn off from the suction side of the pump and only a quantity equivalent to m parts of fuel is being fed to the suction side, an additional quantity equivalent to m parts of oil must be sucked in by way of suction valve 8 from the oil container 7. Accordingly, it is possible to directly read off the quantity of unblended oil fed to the pump 10 from the dial mechanism 16. This means that from every 100 parts of fuel flowing out of volumeter 1 m parts of fuel are being drawn off, while, on the other hand, immediately ahead of the dispensing nozzle 5 and by way of pre-blended mixture proportioner 2 and hose 6 a quantity equivalent to $2m$ parts of oil and fuel is being fed to the discharge nozzle. Accordingly, the mixture dispensed from discharge nozzle 5 contains m parts of oil.

If other liquid admixtures, for example benzol, are used, the technical novelty of the invention consists in that only one pump is required for simultaneously dispensing two types of fuels. It is obvious that it is also possible to arrange for a combination by using one and the same pump for dispensing fuel to which, for example, oil and benzol have been added.

What is claimed is:

1. An apparatus for delivering proportional mixtures of liquid materials, including a source of supply for a primary liquid and a first conduit therefrom to a point of delivery, and a source of supply for a secondary liquid, which comprises a means for forming an initial mixture of a minor portion of the total primary liquid delivered

and a total portion of said secondary liquid proportional to said total primary liquid at said point of delivery; a second conduit for said initial mixture, communicating between said means for forming the initial mixture and said first conduit; a first proportioning pump connected in said second conduit; a flow actuated driving means for driving said first pump connected in said first conduit and actuated by flow of primary liquid therethrough; a first conduit connection between said first conduit and said means for forming said initial mixture; a second proportioning pump in said first conduit connection; a flow actuated driving means for driving said second pump connected in said second conduit; a second conduit connection between said supply source for secondary liquid and said means for forming said initial mixture; and means for regulating said first proportioning pump to supply said initial mixture to said first conduit in which said secondary liquid is present in a predetermined proportion to the total primary liquid.

2. A method for delivering a proportionally blended mixture of a primary liquid and a secondary liquid, characterized by the fact that said secondary liquid is added to and blended with said primary liquid substantially at the point of delivery of said blended mixture as a preblended mixture of proportioned parts of said primary and secondary liquids, which comprises passing a stream of said primary liquid through a first confined flow path to a point of delivery of a blended mixture of primary and secondary liquids, withdrawing a portion of said primary liquid from said first confined flow path upstream from said point of delivery and introducing said withdrawn portion of said primary liquid into a second confined flow path, introducing a portion of said secondary liquid into said second confined flow path and forming therein a preblended mixture of said primary and secondary liquids, passing a stream of said preblended mixture of primary and secondary liquids through said second confined flow path, regulating volumetric flow of said stream of preblended mixture through said second confined flow path according to and in proportion to the total volumetric flow of said stream of primary liquid through said first confined flow path, discharging said stream of preblended mixture from said second confined flow path and combining said discharged stream of the preblended mixture with said stream of primary liquid downstream from the point of withdrawal of primary liquid from said first confined flow path, the withdrawal of primary liquid from said first confined flow path being regulated in proportion to the volumetric flow of said preblended mixture through said second confined flow path, and introduction of said secondary liquid being maintained at a rate substantially equal to the difference between the total volume of said preblended mixture discharged into and combined with said stream of primary liquid, and the volume of said primary liquid introduced into said second confined flow path.
